UNITED STATES PATENT OFFICE.

JOSEPH P. RUTH, JR., OF DENVER, COLORADO.

AERATING DEVICE.

1,268,630.

Specification of Letters Patent. Patented June 4, 1918.

Application filed May 31, 1917. Serial No. 171,891.

To all whom it may concern:

Be it known that I, JOSEPH P. RUTH, Jr., citizen of the United States, residing at the city and county of Denver and State of Colorado, have invented certain new and useful Improvements in Aerating Devices; and I do declare the following to be a full, clear, and exact description of the invention, such as will enable others skilled in the art 5 to which it appertains to make and use the same, reference being had to the accompanying drawings, and to the characters of reference marked thereon, which form a part of this specification.

15 My invention relates to improvements in agitating devices, being more especially intended for use in connection with flotation apparatus or apparatus adapted to cause the metallic values in connection with oil and 20 air to rise to the top of the pulp in the form of a froth.

In apparatus of this character it is exceedingly important that the pulp be properly aerated and the object of my present 25 improvement is to produce a device adapted to efficiently perform this function, though it is evident that my improved agitator may be advantageously employed in other relations.

30 In the embodiment of my improved construction, illustrated in the drawing, the device is well adapted for use in testing ore for treatment by the flotation process, one side of the receptacle being composed of 35 glass whereby the process may be advantageously observed. Furthermore, this glass side member is removable, so that after each test the receptacle may be thoroughly cleaned, in order to prevent the possibility 40 of any metallic values remaining therein from the previous test. It should be explained, however, that the construction is well adapted for use on a large scale as well as in a small testing plant of the character 45 just explained. In my improvement I employ a receptacle into which the pulp mingled with the necessary oil is introduced. Located at the bottom of this receptacle is a rotary head from which extends down- 50 wardly a short, open ended pipe, which is in communication with pulp in the bottom of the tank. A conduit is also connected with this head and extends upwardly therefrom above the level of the pulp, the upper ex- 55 tremity of the conduit being open for the entrance of air. The lower pipe member is

in communication with the inner extremities of a number of passages formed in the head and whose outer extremities terminate at the periphery of the head; while the upwardly 60 extending conduit is in communication at its lower extremity with a number of passages which also extend outwardly to the periphery of the head, the outer extremities of the last named passages, however, being 65 hooded to facilitate the escape of the air from said passages, this air being sucked downwardly through the upwardly extending conduit by the centrifugal force developed by the rotary action. As the head 70 is rotated, the centrifugal force draws pulp from the bottom of the tank and discharges it through certain passages of the head to the periphery of the latter; while the same force draws air downwardly through the 75 upwardly extending conduit into the head and discharges it through other passages at the periphery of the head. The object of hooding the outer extremities of the air 80 passages of the head is to produce a suction 85 adjacent the extremities of these passages whereby the air is caused to escape from the outer extremities of said passages into the pulp.

Having briefly outlined my improvement 85 as well as the function it is intended to perform I will proceed to describe the same in detail, reference being made to the accompanying drawing in which is illustrated the embodiment thereof.

In this drawing Figure 1 is an elevation partly in section illustrating my improved apparatus, the section being taken on the line 1-1 Fig. 2.

Fig. 2 is a top plan view of the structure. 95

Fig. 3 is a vertical section taken through the agitating member proper, shown in detail and on a larger scale.

Fig. 4 is a top plan view of the same.

The same reference characters indicate the 100 same parts in all the views.

Let the numeral 5 designate a tank or receptacle adapted to hold pulp or other material to be treated. As shown in the drawing, the tank is adapted for use as a flotation apparatus and in Fig. 1 the top surface of the pulp is provided with a considerable depth of froth 6. As shown in Figs. 1 and 2 the tank is relatively narrow and provided with vertical side walls 7 and 8 and inclined end 105 walls 9, the end walls being connected at the bottom with a short horizontal member 10. 110

The side and end walls are provided with angle brackets 12 which extend inwardly over the side wall 8, which is preferably composed of glass or other suitable transparent material. In the overlapping ends of these brackets 12 are threaded fastening screws 13 whose inner extremities engage the wall 8 and hold the latter in place but in such a manner that it is readily movable for the purpose of cleaning out the material and sediment therein after any test or after any batch of ore or other material has been treated. The bottom of the tank is provided with an opening 14 which is normally closed by a screw plug 15 which is provided with a lever arm 16 for convenience of manipulation.

Mounted upon the upper part of the structure is an upright frame work 17 having cross-pieces 18 in which is journaled a vertically disposed shaft 19 carrying a pulley 20, which may be connected with any suitable motor, not shown, for the purpose of rotating the shaft. As shown in the drawing the shaft is supported by means of ball-bearing members 21 which are fast on the shaft and engage ball cups carried by the cross-pieces 18. This or any other suitable construction may be employed for supporting the shaft in a stable position in the performance of its function, as hereinafter described. This shaft extends downwardly, its lower extremity terminating at the bottom of the tank where it is threaded into the agitating member proper, which is designated by the numeral 22. This member consists of a head 23 which is provided with a socket 24 into which is threaded the lower extremity of a tube or conduit 25. Below the threaded opening 24, the head is further provided with an opening 26 into which is threaded the lower extremity of the shaft 19. The shaft 19 is relatively small and leaves considerable space within the conduit 25 through which air is drawn downwardly into the head, the upper extremity of the conduit being open and terminating above the level of the material and froth in the tank.

The lower extremity of the conduit 25, within the agitating head is provided with a number of openings 27 which are in communication with the inner extremities of the passages 28 formed in the head, their outer extremities terminating at the periphery of the head and being covered with hoods 29 which are open as shown at 30 for the escape of air into the pulp. The agitating member is rotated in the direction indicated by the arrow *a* in Fig. 4 and the hoods 29, which extend outwardly a short distance from the periphery of the head at their open extremities are curved or inclined inwardly their inner extremities merged into the periphery of the head. Hence, as the head is rotated in the direction indicated by the ar-

row *a*, assuming that the tank contains pulp or other liquid as indicated in Fig. 1, a partial vacuum will be produced adjacent the open extremity of each hood. Assuming that the agitating member is rotated at sufficient speed, this vacuum will be sufficient to overcome the pressure of the head of liquid in the tank and cause the air which is drawn downwardly through the conduit 20 to be forced outwardly into the liquid, whereby the same will be thoroughly aerated, this aeration co-operating with the outward flow of liquid through the head in a manner which will now be explained.

The bottom of the agitating member 23 is provided with a short vertically disposed passage 31 which is open at the lower end of the head and merges into a short downwardly extending tube 32 which is open at its lower end and terminates a short distance from the bottom of the tank. The short passage 31 is in communication with the inner extremities of three passages 33 which lead outwardly from the passage 31 to the periphery of the head. As the head is rotated in the manner heretofore described, the centrifugal force developed by the rotary action of the head will draw the pulp upwardly from the bottom of the tank through the short passage 31 and force it outwardly through the passages 33, producing a thorough agitation of the pulp and a thorough mingling of the air and pulp through the medium of the agitating head. As shown in the drawing a partition 34 is secured between the sides of the tank and is so shaped that it is parallel or approximately parallel with the bottom and inclined ends thereof. The short pipe member 32 extends through an opening in the bottom of this partition and during the operation heretofore explained, pulp is drawn upwardly from below the partition and is discharged against the inclined sides thereof, whereby it is deflected upwardly and facilitates the carrying of the mineral-laden froth composed of the metallic values, oil and air bubbles to the top of the pulp within the tank.

As shown in the drawing the tank is further provided with inclined deflectors or baffle plates 35 which are arranged near the top of the tank.

As shown in the drawing a launder 36 is arranged at each end of the tank and the froth 6 is caused to overflow thereinto, being carried by the launder to any suitable receptacle, whereby it may be treated in any well known or desirable manner.

From the foregoing description the use and operation of my improvement will be readily understood.

The pulp to be treated is fed into the tank by way of a valve-controlled conduit 37, it being assumed that this pulp is min-

gled with the necessary oil, in case the apparatus is to be employed for separating mineral values on the flotation principle. The agitating head or member 23 is rotated 5 at the desired speed, as heretofore explained, and draws air downwardly through the conduit member 25 and discharges it at the periphery of the head, pulp being drawn upwardly into the head simultaneously and 10 also discharged at the periphery of the head through other passages, thus causing the air and the pulp to be thoroughly mingled, as heretofore explained.

The relative number of air and liquid 15 passages in the head may be varied to control the proportions of air and liquid discharged through the head.

Having thus described my invention, what I claim is:

20 1. Aerating apparatus including a tank, a rotary member located therein and provided with a set of passages extending from its central portion toward its periphery, and a hollow member through which said 25 passages are in communication with the atmosphere above the liquid which the tank is adapted to contain, and another set of similar passages having both ends of each passage in communication with the liquid in the 30 tank.

2. Aerating apparatus including a tank, a rotary member located therein and provided with a passage extending from its central portion to its periphery, and a hollow member through which said passage is in communication with the atmosphere above the liquid which the tank is adapted to contain, and another similar passage having both of its ends in communication with the 35 liquid in the tank.

3. Aerating apparatus including a tank, a rotary member located therein and provided with a plurality of independent passages extending from its central portion to its periphery, and a hollow member through which said 40 passages are in communication with the atmosphere above the liquid, which the tank is adapted to contain, and another passage having both of its ends in communication with the liquid in the tank, and means for rotating the said member at a 45 speed to develop sufficient centrifugal force to overcome the pressure of the liquid in the tank, whereby air and liquid are taken into 50 the said member and discharged at its periphery.

55 4. Aerating apparatus including a tank, a rotary member located therein and provided with an open-ended passage extending from 60 its central portion to its periphery and a hollow member through which said passage is in communication with the atmosphere above the liquid which the tank is adapted to contain, a hood at the outer extremity of 65 the air passage and another passage having

both of its ends in communication with the liquid in the tank.

5. Aerating apparatus including a tank, a rotary member located therein and provided with a number of open-ended passages extending from its central portion to its periphery and a hollow member open to the atmosphere above the liquid which the tank is adapted to contain, and in communication at its lower end with said passages, hoods 70 at the outer extremities of the said passages, and a number of other passages in communication at both of their extremities with the liquid in the tank, said last named passages extending from the central portion of the 75 said member to its periphery.

6. Aerating apparatus including a tank, a member mounted to rotate therein and composed of a head having a number of passages extending from its central portion outwardly to its periphery, a tubular member connected with the head and extending above the liquid in the tank, said tubular member being open to the atmosphere at its upper extremity and in communication at its lower 90 extremity with the passages of the head, the rotary member having a depending conduit open at its lower extremity to allow the liquid of the tank to enter, the rotary member having a number of passages in communication with the said liquid-receiving conduit, said last named passages being open-ended and extending from the central portion of the rotary member to its periphery. 95

7. Aerating apparatus including a tank, a vertically disposed shaft extending into the tank, a rotary member secured to the lower portion of the shaft and having two sets of passages extending outwardly from its central portion to its periphery, one set of said 100 passages having hoods at their outer extremities, a conduit whose lower extremity is secured to the said rotary member and in communication with the hooded passages, the upper extremity of said conduit being in communication with the atmosphere above the liquid of the tank, the rotary member having a depending conduit in communication with the other set of passages both extremities of the latter thereby being in communication with the liquid in the tank. 110

8. A gas diffusion device comprising a rotary head having a passage for gas therein extending outwardly toward the periphery 115 of the head and a stationary hood at the outer extremity of said passage.

9. A gas diffusing device comprising a rotary head having a plurality of passages for gas extending outwardly toward the periphery of the head and stationary hoods at the outer extremities of the passages. 125

10. A gas diffusing device comprising a rotary head having a plurality of passages for gas extending outwardly toward the pe- 130

4

riphery of the head, stationary hoods at the outer extremities of the passages, and a set of liquid passages extending outwardly from the center toward the periphery of the head.

11. A gas diffusing device comprising a rotary head having a set of passages for gas extending outwardly away from the center toward the periphery of the head, and a set 10 of liquid passages also extending toward the periphery, all of said passages being open at both ends.

12. A gas diffusion device comprising a rotary member having a passage for gas 15 therein extending outwardly from the center of the member, said passage having an outlet, and a stationary member arranged adjacent said outlet and adapted to displace liquid passing said outlet.

13. A gas diffusion device comprising a 20 rotary head having a passage for gas therein extending outwardly from the center of the head, said passage having an outlet, and a relatively stationary hood arranged adjacent said outlet and adapted to displace liquid 25 passing said outlet to create a partial vacuum to draw out the gas.

14. A gas diffusing device comprising a rotary head having a plurality of passages for gas extending outwardly from the center 30 of the head, each passage having an outlet in its outer portion, and a relatively stationary hood arranged adjacent each of said outlets and adapted to displace liquid passing said outlets to create a partial vacuum to 35 draw gas into the liquid.

In testimony whereof I affix my signature.
JOSEPH P. RUTH, JR.
